UNITED STATES PATENT OFFICE.

OSCAR RAADE, OF PELICAN RAPIDS, MINNESOTA.

COMBINED KNIFE AND SAW.

1,047,838.

Specification of Letters Patent. Patented Dec. 17, 1912.

Application filed May 23, 1911. Serial No. 629,033.

To all whom it may concern:

Be it known that I, OSCAR RAADE, a citizen of the United States, residing at Pelican Rapids, in the county of Ottertail, State of Minnesota, have invented certain new and useful Improvements in Combined Knives and Saws; and I do hereby declare the following to be a full, clear, and exact description of the invention, such as will enable others skilled in the art to which it appertains to make and use the same.

This invention relates to a combined knife and saw, and has for its object to construct a device of this character with simple and efficient means for holding and adjusting a knife and saw blade in a rigid and stretched position.

With these and other objects in view, the invention consists in the construction and novel combination of parts hereinafter fully described, illustrated in the accompanying drawings, and pointed out in the claim hereto appended; it being understood that various changes in the form, proportion, size and minor details of construction, within the scope of the claim, may be resorted to without departing from the spirit or sacrificing any of the advantages of the invention.

30 In the drawing:—Figure 1 is a side elevation of the device. Fig. 2 is an end view of the same. Fig. 3 is a fragmentary view of the rear end of the device, partially in section. Fig. 4 is a sectional view on line 35 4—4 of Fig. 1.

Referring to the drawing, the numeral 5 designates a bar having its inner and outer ends 6 and 7, respectively, reduced and screw threaded.

40 A pair of inner and outer stretcher bars 8 and 9, respectively, are employed the inner bar being provided with a threaded perforation 10, and the outer bar 9 having formed therein an unthreaded perforation 45 11. The opposite ends of the bars 8 and 9 are provided with kerfs 12 in which the opposite ends of the knife blade 13 and saw blade 14 are secured in any suitable manner.

The reduced end 7 of the bar 5 carries an 50 adjusting nut or stop 15 which is threaded thereon before said extension is passed through the perforation 11. After the bar

9 has been placed on the extended end of the threaded portion 7 of the bar 5 an adjusting nut or stop 16 is placed thereon, the object of which will be hereinafter described.

The reduced end 6 of the bar 5 is threaded through the perforation 10 of the bar 8, the same projecting slightly beyond the outer edge of said bar. A handle is provided and consists of a base 17 and convergingly arranged arms 18, the outer ends of which are perforated for the reception of a bolt 19, and upon which is mounted a wooden grip 20. The base 17 is formed with a central perforation 21 and is adapted to be secured in place upon the bar 8 after the same has been passed over the reduced threaded portion 6 of the bar 5. A clamping nut 22 is threaded upon the extended portion of the reduced end 6 to firmly clamp the handle. After the knife blade 13 and saw blade 14 have their opposite ends placed in the kerfs 12 formed in the ends of the stretcher bars 8 and 9 the same may be stretched upon manipulation of the adjusting nuts 15 and 16, the nut 15 after adjustment of the stretcher bar 9 prevents the accidental retraction of said blades.

80 What is claimed, is:—

In a device of the class described, the combination of a bar having threaded terminals, nuts threaded upon said terminals and abutting the ends of the bar proper, stretcher bars disposed upon said threaded terminals in contact with the nuts, tools extending between and connected with the ends of the stretcher bars, a nut threaded upon a terminal of the bar and engaging the adjacent stretcher bar, a handle including a plate carried by the opposite threaded terminal of the bar and engaging the adjacent stretcher bar, arms extending from said plate and a grip member connecting the arms, and a nut threaded upon the last mentioned terminal of the bar and contacting with the plate.

In testimony whereof, I affix my signature, in presence of two witnesses.

OSCAR RAADE.
